UNITED STATES PATENT OFFICE.

ROBERT GOODWILL, OF SHAMOKIN, PENNSYLVANIA.

DESIGN FOR A BED-WARMER.

SPECIFICATION forming part of Design No. 24,583, dated August 20, 1895.

Application filed July 6, 1895. Serial No. 555,166. Term of patent 14 years.

To all whom it may concern:

Be it known that I, ROBERT GOODWILL, of Shamokin, in the county of Northumberland and State of Pennsylvania, have invented and produced a new and original Design for a Bed-Warmer, of which the following is a full, clear, and exact description.

Reference is to be had to the accompanying drawings, forming a part of this specification, o in which—

Figure 1 represents a perspective view of a bed-warmer embodying my design, and Fig. 2 is an end view of the same.

The leading feature of my design consists in the elongated body of rounding form, except at the bottom, which presents a flat surface, said body at the top presenting a neck-like protuberance at the center and ears near the ends. 15

I claim—

The design for a bed-warmer herein shown and described. 20

ROBERT GOODWILL.
